ILLUMINATING MOTOR TOOL

Godfrey Dalkowitz, Brooklyn, N. Y., assignor to
 American Safety Razor Corporation, Brooklyn,
 N. Y., a corporation of Virginia

Application March 10, 1939, Serial No. 260,907

4 Claims. (Cl. 172—36)

This invention relates to shaving appliances and more particularly to that type of shaving appliance known as dry shavers, in which the shaving operation is effected without the aid of shaving soaps, creams, or the like.

More specifically my invention relates to a dry shaver having incorporated therein means for illuminating the area to be shaved.

The general object of my invention is the provision in such a dry shaver of a simple, reliable, economical and effective construction.

Among the more particular objects of my invention are the provision in a dry shaver, of an illuminating arrangement for the area to be shaved forming part thereof; the provision in an electrically operated dry shaver of an illuminating arrangement energized from said operating means; the provision in a dry shaver of operating means and illuminating means and a single control therefor; the provision in a dry shaver having an electric motor of the magnetic type therein, of illuminating means, and an arrangement whereby said means is energized from the motor; the provision in a dry shaver having an electric motor therein and illuminating means, of an arrangement for energizing said illuminating means from the motor at a lower voltage than is supplied to the motor; and the provision in an electrically operated dry shaver of means for eliminating interference with other apparatus, such as radio sets and the like, when the dry shaver is connected to the same circuits therewith.

These objects and such other objects as will hereinafter appear or be pointed out, are attained in the illustrative embodiment of my invention shown in the drawings, in which—

Figure 1 is a plan view of my improved dry shaver with the upper portion of the casing removed so as to expose the interior construction;

Figure 2 is a transverse sectional view taken substantially on the line 2—2 of Figure 1 looking in the direction of the arrows;

Figure 3 is a fragmentary plan view taken substantially on the line 3—3 of Figure 2, looking in the direction of the arrows, with the cover of the recess in which the light is positioned, removed;

Figure 4 is a view of a portion of Figure 3, with the parts of the starting mechanism in a different position;

Figure 5 is a sectional view substantially on the line 5—5 of Figure 4, looking in the direction of the arrows;

Figure 6 is a transverse sectional view sub-

stantially on the line 6—6 of Figure 1, looking in the direction of the arrows; and

Figure 7 is a diagrammatic view showing the electrical circuits.

Referring to the drawings for a detailed description of the illustrative embodiments of my invention shown therein it will be observed that I have provided a casing C adapted to receive the operative parts of my dry shaver and also to carry the shaving head, indicated in dot and dash lines, and designated by the letter S. The casing C is conveniently made in two parts 10 and 11 that may be assembled, as by screws, to form a substantially closed casing, and that is readily opened, when desired, to expose the interior mechanism.

In order to secure a casing that is as light as possible and yet nevertheless strong to perform its function of protecting the operating mechanism of the shaver I may make parts thereof thicker and connect these by thin webs. Among the thickened portions may be mentioned the ribs 12 and 13 which reinforce the casing and also serve to support the interior parts of the dry shaver as will hereinafter appear, and further portions 14 (see Figures 1 and 2) through which may pass screws 14a for fastening together the two parts 10 and 11 of the casing C, the upper portions of these screws passing freely through one of the parts 10 and 11 and their lower ends being in threaded engagement with the other of the parts 10 and 11.

At the midportion of each of the parts 10 and 11 is shown a post-like brace, these being numbered 14a and 14b respectively and being long enough to meet each other. A screw 14c is shown passing freely through one end threaded into the other. The value of these braces in strengthening the casing at its midportion can be readily appreciated.

The operative parts of the shaver comprise a motor adapted to actuate a lever, which latter has a portion extending into the shaver head for the purpose of imparting movement to the parts thereof. Associated with the motor is a starting mechanism for the same, and, as will appear as the description proceeds, the starting mechanism has embodied therein, or associated therewith, a switch by means of which the current supplied to the motor may be cut off when desired. Suitably housed within the confines of the casing of the dry shaver I have provided illuminating equipment adapted to illuminate the area to be shaved, and this illuminating equipment is controlled by the switch that has just been men-

tioned in connection with the motor and is electrically associated with the motor so that its circuits in effect form a part of the motor circuits.

Adjunctive to the motor circuits is a system of capacitances adapted to improve the functioning of the motor and the illuminating equipment and to minimize their disturbing effect on radio apparatus connected to the same line.

The motor is shown as of the magnetic or impulse type, that is of the type in which the field magnet is intermittently energized, and the armature is an unwound member of magnetic material adapted to be given a rotating impulse whenever the field magnet is energized. By means of a cam arrangement on the motor shaft the timing of the field circuit energizations is effected in synchronism with the rotation of the armature, and thereby the impulses acting on the latter are so timed that continuous rotation results.

The field magnet of the motor is designated by the numeral 16. It is shown as of laminated horse-shoe construction and as resting on the ribs 12 and 13 and secured in place by screws 17 and 18.

A pair of insulating plates 19 and 20 are shown supported respectively above and below the pole portions of the field magnet and within these is journaled the armature shaft 21 carrying an armature 22 shown as of hour glass form and as of laminated construction. For the purpose of energizing the field magnet I have shown a compound coil 23 mounted on the yoke portion of the field magnet, and comprising two coils 23a and 23b inductively coupled together to form a step-down transformer, of which the coil 23a is the primary and of which the coil 23b is the secondary (see Figure 7). The coil 23b serves to energize an incandescent filament bulb 25 the details of which and the mounting of which will be hereinafter described more fully.

The operating lever 26 is shown as having a pair of pintles 27 and 28 extending in opposite directions therefrom. The pintle 28 is journaled in the upper half of the casing 10 and the pintle 27 is journaled in a member 29 suitably secured to the casing section 10 as by screws 30.

The inner end of the lever is suitably contoured so that its nose portion extends beneath the underside of the armature, and at this point it is provided with an enlarged head 31 having a slot 32 therein into which projects an eccentric 33 which is shown as engaging the side walls of a slot 34 in an insulating plate 35 suitably secured to the head 31 as by rivets 36. As the armature shaft rotates the plate 35 will be caused to move laterally by the eccentric 32 and to operate a make and break system by which the operation of the motor is effected. At the same time, and as a further consequence, the nose portion 37 of the lever which extends into the shaving head is caused to oscillate and to reciprocate the parts of the shaver head which it engages.

The make and break system of the motor is shown as comprising two sets of contact points connected in series with each other and with the field coil 23a.

The details of the make and break system will now be explained with the aid of Figures 1, 2 and 6 showing the arrangement of parts, while their function in the electrical circuits is shown in Figure 7.

Mounted on the field magnet 16 is shown a non-conducting plate 38, secured in place by the screws 17 and 18 which serve to hold the field magnet in

the casing, and this plate carries a conducting bracket 39 from which project a pair of resilient fingers 40 and 41, each carrying a contact point, respectively 42 and 43, adjacent its free end portion.

Carried one on each one of extensions 44 and 45 of the plate 20 are shown brackets 46 and 47 (see Figure 6), each provided with a U-shaped end portion on the free end of which is positioned a contact point, respectively designated 48 and 49, opposed to one of the aforementioned contact points 42 and 43.

In order to permit of adjustment of the contact points 48 and 49 relatively to the contact points 42 and 43 I have shown an arrangement comprising set screws 50 and 51 which are threaded respectively through the brackets 46 and 47 and press with their nose portions against the contact carrying legs of the brackets, the latter being made resilient so that they will follow the nose portions of the set screws 50 and 51 as they are retracted.

The respective pairs of contacts 42 and 48, and 43 and 49 are connected in series with each other, through the conducting bracket 39 as already described, and in series with the coil 23a, and they are further in series with a switch 52, to be hereinafter more fully described.

It is to be understood that when the plate 35 is in its middle position, both sets of contact points 42, 48 and 43, 49 are closed. As the plate 35 moves from its middle position it alternatively opens first one set of contact points and then the other.

35 A condenser 53 (see Fig. 7) is shown shunted across both sets of contact points 42, 48 and 43, 49, and a second condenser 54 is connected across the line. Both of these condensers in the practical embodiment of my invention are conveniently mounted so as to constitute a single unit designated by the numerals 55 (see Figures 1, 2).

The condenser 53 serves to absorb the high voltage high frequency currents that occur whenever one of the sets of contacts 42, 48 or 43, 49 is broken, and thereby the high peak voltages and the arcing effect occurring between the contacts on each break are reduced. In this respect its function is conventional. It has, however, the further function of reducing peak voltages on the lamp 25, which it accomplishes as a consequence of its aforementioned conventional function, because the peak voltages in the coil 23a being reduced, the peak voltages induced in the coil 23b are likewise reduced.

55 The condenser 54 is intended to eliminate radio interference, that is interference with the operation of radio receiving sets connected to the same circuit. In this respect it supplements the condenser 53 which also tends to some degree to eliminate radio interference.

The condensers 53 and 54 are conveniently mounted together so as to form a single unit 55 (see Figures 1 and 2).

In order to effect these connections I have shown a pair of conductors 56 and 57 running from the terminals 58 and 59, mounted on an insulating plate 60, to the terminals of the condenser 54. The plate 60 is shown fitting into grooves in the casing sections 10 and 11 so as to be held in place therein when the sections are assembled. An insulating partition, 61, shown as of sheet material suitably folded, serves to prevent contact of parts connected to the terminals 58 and 59 and thereby to prevent short circuits.

A conductor 62 is shown connecting the terminal 56 with one pole 63 of the switch 52. From the other pole 64 of the switch a conductor 65 is shown running to one terminal of the field coil 23a. Conductor 66 connects the other terminal of the field coil and the contact 49, while the contact 48 is connected to the common terminal of the condensers 53 and 54, to which the conductor 57 is also connected, by a conductor 61. A conductor 68 connects the remaining terminal of the condenser 53 with the conductor 66, and through it with one terminal of coil 23a.

A pair of conductors 69 and 70 is shown connecting the terminals of the coils 23b to a pair of clips 71 and 72 adapted to receive the ferrules 73 of the lamp 25. Through the conductors 69 and 70 the clips 71 and 72 and the ferrule 73 the current from coil 23a is led into the incandescent filament 74 of the lamp 25, which, it will be observed, is shown as of "cartridge" type, comprising a transparent tubular casing 75 having the aforementioned ferrules 73 at its ends and having a straight incandescent filament 74 connected at its ends to said ferrules 73. It will be observed that by this arrangement the lamp 25 is readily inserted into the recess 76 provided in the casing section 10 for the reception of said lamp, and within which recess said clips 71 and 72 are mounted.

The recess 76 has an opening 76a in its foremost wall leading into a recess 77 in the casing 10, and through this recess the light passes to illuminate the area of the face adjacent the shaving head S during the shaving operation. In order to increase the efficiency of this arrangement I have shown a reflector 78 in back of the incandescent lamp 25 so positioned as to throw the light therefrom forward and through the aforementioned cut-away portion 77.

A removable cover 79 adapted to be positioned over the top of the recess 76 is provided which prevents the escape of light in this direction and thereby limits the opening through which light is emitted to the aforementioned opening 76a of the recess. This cover may be provided with resilient extensions 80 which are adapted to spring into suitable complementary portions of the walls of the recess 76 and hold the cover in place. When it is desired to remove or insert the lamp 25 into the recess the cover is first removed.

The clips 71 and 72 are preferably made resilient so that to insert a lamp thereinto requires merely sufficient pressure to cause them to spread and to remove the light it is merely necessary to impart sufficient pull to overcome the resilient grip of these clips.

The reflector 78 is conveniently mounted by having one portion thereof extending laterally so that one or both of the rivets 81 that hold the clips 71 and 72 in place on the casing section 10 may be passed through said extended portions. In the drawings it is shown as having an extension passing underneath the clip 72, but not underneath the clip 71.

In order to start the motor I have shown an arrangement for giving a spinning impulse to the armature and for closing the switch 62 after the armature has been given such impulse. This arrangement may comprise a toggle mechanism which tends to assume one of two limiting positions and during passage from one of said positions to the other serves to impart a rotating impulse to the armature shaft through mechanism associated therewith.

The starting mechanism, the details of which will be found fully illustrated in Figures 2, 3, 4 and 5 is shown as comprising first of all a lever 82 pivoted as shown at 83 to a plate 83a, suitably mounted on the field magnet 16 as by rivets 83b passing through the plate and through the magnet and the lever 82 is provided with a slot 84 into which is shown projecting a stud 85 carried by a thumb piece 86 that is slidable on the outside of the casing 10 as clearly shown in Figure 2. The piece 86 is mounted in a position convenient for manipulation by the thumb of a person engaged in shaving himself, without changing his grip on the shaver.

15 The stud 85 passes through a slot 87 in the casing and the thumb piece 86 is held against the wall of the casing by some means such as a leaf spring 88. On moving the thumb piece 86 the lever 82 will be moved, and by mechanism that will be hereinafter described in detail, the lever 82 will be caused automatically to assume one of its two limiting positions. A stop member 89 may be provided to prevent movement of the lever 82 beyond these limiting positions.

20 The lever 82 carries a pawl 90 pivotally mounted thereon at 91 and adapted for limited angular movement about said pivot, this angular movement being limited by a stop 92 carried by the lever 82 and adapted to engage suitable lugs 93 provided on the pawl 90. The pawl is further provided with an extension 94 (see Figure 5) adapted to project into the path of the teeth of a ratchet 95 carried on the armature shaft 21.

25 Pivots attached to the pawl 90 at 96 is shown a rod 97, the other end of which is slidable in a lug 98 provided on one arm 99a of a bell crank lever 99 pivotally mounted at 100 on the aforementioned plate 83b. A compression spring 101 tends to urge the rod 97 away from lug 98 and thereby to cause the lever 82 to assume either one of the aforementioned limiting positions. The other arm 99b of the lever 99 carries a cam block 102, preferably of insulated material, that is adapted to engage a resilient extension 103 of the pole piece 53 of the switch 52 when the lever is moved into the position shown in Figure 4, and to move the same into engagement with the extension 104 of the pole 64 of the switch 52 and thereby to close the switch.

30 50 The limiting positions of the lever 99 are determined by a stop member 105.

Assuming that the parts of the starting mechanism are in the position of Figure 4, which is their operating position which they assume after 55 the armature has been given a starting impulse, if it is desired to stop the shaver the parts must be moved into the position of Figure 3. This is done by moving the thumb piece 86 from the dot and dash line position of Figure 2 into its full line position of the same figure. The stud 85 which is attached to the said thumb piece and which, it will be recalled, engages the slot 84 of the lever 82, then moves the said lever into the position of Figure 3. The pawl 90 in its end 60 position as shown in Figure 3 has been displaced pivotally about its pivot 91 and the lever 99 has moved into a position in which the cam block 102 releases the extension 103 of the switch 52 and the switch opens. During this movement the lug 94 of the pawl is outside of the path of the teeth of the ratchet 95, this being due to the pivotal movement of the pawl 90 about the pivot 91.

65 70 75 In order to start the motor the parts are

brought from the position of Figure 3 to that of Figure 4. This is accomplished by moving the thumb piece 86 from its full line position in Figure 2 to its dotted line position in said figure. By this movement the lever 82 is caused to move into its position as shown in Figure 4, and the lug 94, which, as clearly appears from Figure 3, is now in a position to engage the teeth of the ratchet 95, will be caused to spin the ratchet 95 and with it the armature shaft as the lever moves from its position of Figure 3 to that of Figure 4. Shortly after the spinning movement of the ratchet 95 has begun the cam block 102 of the lever 99 will move into a position in which it will close the switch as shown in Figure 4. The effect of the movement of the armature concurrently with the closing of the switch will have the effect of causing the motor to start, in accordance with the well known principles governing motors of this type.

While I have herein disclosed one embodiment of my invention it will be understood that the same may be embodied in many other forms without departing from the spirit thereof, as will be obvious to those skilled in the art, and that the disclosure herein is illustrative merely and is not to be interpreted in a limiting sense, and that I do not limit myself other than as called for by the prior art.

Having thus described my invention and illustrated its use, what I claim as new and desire to secure by Letters Patent is:

1. In combination, a motor, a casing to house the parts thereof in the form of a shell composed of two interfitting sections, and a pair of opposed rod-like members projecting from the midportions of the interior walls of said sections, so as to meet and thereby to constitute a pillar-like strut resisting collapse of the casing.

2. Starting means for an electric motor of the impulse type, said means comprising a casing for the motor, a thumb-piece, a slidable mounting for said thumb-piece in said casing, a lever, a mounting for said lever for supporting it in pivotal relation to the motor, a connection between said thumb-piece and said lever whereby when the thumb-piece is moved said lever will be moved about its pivot, said connection comprising a slot in one of said members and a pin in the other of said members engaging said slot, a pawl pivotally mounted on said lever at a point removed from the pivot of said lever, a pin having one end pivoted to the pawl, a switch for the motor circuit mounted in the casing, a member pivoted on the motor frame for closing said switch, an opening in said member to re-

ceive said pin in slidable engagement, and a coil spring carried by said pin and acting between said pin and said member so as to tend to cause the pin, the member, the pawl and the lever to move to one side or the other of a dead center position, complementary means on said pawl and on the rotor shaft of the motor for causing rotation of the rotor shaft when the pawl is moved and said complementary means are in interengagement, whereby when said thumb-piece is slid in one direction the pawl will act to give a starting impulse to the rotor shaft and the member will act to close the switch, while when said thumb-piece is moved in the opposite direction the switch will be opened.

3. Starting means for an electric motor of the impulse type, said means comprising a thumb-piece, a slidable mounting for said thumb-piece, a pivotally mounted lever, a connection between said thumb-piece and said lever whereby when the thumb-piece is moved said lever will be moved about its pivot, a pawl pivotally mounted on said lever at a point removed from the pivot of said lever, a pin having one end pivoted to the pawl, a switch for the motor circuit, a member pivoted on the motor frame for closing said switch, an opening in said member to receive said pin in slidable engagement, and a coil spring carried by said pin and acting between said pin and said member so as to cause it to move to one side or the other of a dead center position, complementary means on said pawl and on the rotor shaft of the motor for causing rotation of the rotor shaft when the pawl is moved and said complementary means are in interengagement, whereby when said thumb-piece is slid in one direction the pawl will act to give a starting impulse to the rotor shaft and the member will act to close the switch, while when said thumb-piece is moved in the opposite direction the switch will be opened.

4. An electric motor of the magnetic type having an armature carried on a rotatable shaft and a field coil, and means for periodically interrupting the current in said coil, said means comprising two pairs of contacts connected in series with each other and with the field coil, and the contacts of each pair being normally closed and mechanism operated from the armature shaft for alternately opening said contacts, a second coil magnetically coupled to said first coil, means for converting electricity into light connected across said second coil, a capacitance connected across said interrupting means, and a capacitance connected across the input terminals of the motor.

GODFREY DALKOWITZ.
